UNITED STATES PATENT OFFICE

2,574,410

FLOOR RACK

Arthur F. O'Connor, Chicago, Ill., assignor to
 Union Asbestos & Rubber Company, a corpora-
 tion of Illinois

Application July 22, 1946, Serial No. 685,426

4 Claims. (Cl. 105—375)

1

This invention relates to floor racks and more particularly to lading supporting racks for railway refrigerator cars and the like.

In railway refrigerator cars it has been customary to support the lading on racks resting on the car floor and hinged to the sides of the car so that they can be raised for cleaning the floor. When operating over rough tracks or at high speeds with cars of this type, the lading has frequently been damaged due to bouncing of the car. It is accordingly one of the objects of the present invention to provide a floor rack for use in railway refrigerator cars and the like in which damage to the lading during operation on rough tracks or at high speed is minimized or eliminated.

Another object is to provide a floor rack which is vertically resilient to absorb vertical shocks incurred during operation.

Still another object is to provide a floor rack including stringers supporting slat means above a car floor in which stringers are so constructed as to be vertically resilient. Preferably the stringers are formed by supporting blocks to which supporting strips are connected for yielding vertical movement.

Still another object is to provide a floor rack which is vertically resilient and which provides a snubbing action to minimize or eliminate bouncing of the lading.

The above and other objects and advantages of the invention will be more readily apparent from the following description when read in connection with the accompanying drawing, in which—

Figure 1 is a partial section through a portion of a railway car and a floor rack embodying the invention;

Figure 2 is a partial plan view;

Figure 3 is a section on the line 3—3 of Figure 1.

Figure 4 is a view similar to Figure 1 of an alternative construction; and

Figure 5 is a section on the line 5—5 of Figure 4.

As shown in Figure 1 the rack is mounted in a refrigerator car having a floor 10 and a side wall 11 supported by an elongated side beam 12. The construction illustrated is a conventional refrigerator car structure, and it will be understood that the rack of the present invention might be applied to any desired type of car.

The floor rack comprises two or more parallel stringers each extending the full length of the rack and each of which includes a supporting block 13 which may be formed of any desired ma-

2

terial such as wood and an inverted channel-shaped supporting strip 14 which fits slidably over the block 13. A bolt 15 secured to the sides of the strip 14 extends through a vertically elongated slot 16 in the block so that the strip can move vertically relative to the block through a limited distance. The rack is completed by cross slats 17 which may be in the form of inverted metal channels preferably perforated to provide for air circulation which extend across and are secured to the supporting strips 14 as by welding or the like. It will be understood that a plurality of substantially identical racks are provided to form a complete lading supporting floor for the car.

In order that the lading may be yieldingly supported, spring means are provided within the channel shaped supporting strips to urge the supporting strips upward relative to the blocks 13. As shown in Figures 1 and 3 the spring means may comprise one or more elongated sinuous spring strips 18 which engage the lower surface of the web of the channel shaped supporting strips 14 and which rest on a metal wear strip 19 on top of the block 13. To prevent shifting of the spring strips as they elongate under load, each strip may be secured at one point to the wear strip 19 by a rivet 20.

The construction is shown in Figures 1 and 3 in fully expanded position with the supporting strip 14 raised to its maximum elevation relative to the block 13. When the rack is loaded, the spring 18 will be deflected to permit the supporting strip to move downward on the block. The spring 18 may be so designed as to permit the supporting strip 14 to move down so that the edges of its flanges will seat against the floor of the car under normal load conditions or it may, as preferred, be of a strength to hold the supporting strip yieldingly above the car floor. In either case the supporting strip and the slat structure 17 will move up and down on the supporting blocks as the car encounters vertical bumps or other rough conditions yieldingly to absorb shocks so that they will not be transmitted to the lading to damage the lading. Due to the frictional engagement of the loops in the spring strip 18 with the supporting strip 14 and the wear strip 19, a snubbing action will be produced which will prevent development of harmonics in the spring to cause bounding of the lading. Thus with this construction the lading is yieldingly supported so that it will not be damaged when operating on rough track or at high

speed.

30 35 40 45 50

The rack, as shown, may be pivotally connected to the car so that it can be swung upward for cleaning the car floor in the same manner as a conventional rack. For this purpose hinge brackets 21 are secured to the supporting strips 14 which lie adjacent one edge of the car and carry horizontal hinge pins 22. U-shaped hinge parts 23 are secured to the side of the car as, for example, to the beam 12 as shown in Figure 1 and are formed with vertically elongated slots 24 into which the ends of the pins 22 extend. With this construction the rack may move vertically without interference from the hinge and still may be swung to a vertical position for conventional cleaning of the car floor.

Figures 4 and 5 illustrate an alternative structure which is substantially similar to that shown in Figures 1 to 3 and in which like parts are designated by the same reference numerals. In this construction the sinuous spring 18 of Figures 1 to 3 is replaced by rubber blocks or strips 25 which lie on top of the supporting block 13 and engage the lower surface of the channel web. If desired, individual spaced rubber blocks 25 may be employed or the blocks may be formed with openings therethrough, as shown at 26, to provide for flow of the rubber. This construction operates in substantially the same manner as that of Figures 1 to 3 except that the vertical loads are absorbed by resiliency of the rubber rather than by flexing of the spring strip. It will be noted that the rubber itself provides a certain inherent snubbing effect, and additional snubbing is produced by friction of the rubber against the sides of the channel 14 and against the upper surface of the supporting block 13 as the rubber distorts during operation.

While two embodiments of the invention have been shown and described in detail herein, it will be understood that they are illustrative only and are not intended as a definition of the scope of the invention, reference being had for this purpose to the appended claims.

What is claimed is:

1. A floor rack for railway cars and the like comprising a plurality of stringers and slats supported on and connecting the stringers, each of the stringers comprising an elongated supporting block coextensive in length with the floor rack to rest on the floor of the car, an inverted channel shaped supporting strip coextensive with and fitting slidably over the block, means connecting the strip and block for limited vertical movement, and resilient means connecting the strip and block to urge the strip upward relative to the block.

2. A floor rack for railway cars and the like comprising a plurality of stringers and slats supported on and connecting the stringers, each of the stringers comprising an elongated supporting block coextensive in length with the floor rack to rest on the floor of the car, an inverted channel shaped supporting strip coextensive with and fitting slidably over the block, means connecting the strip and block for limited vertical movement, and spring means within the channel shaped strip engaging the top of the block to urge the strip upward relative to the block.

3. A floor rack for railway cars and the like comprising a plurality of stringers and slats supported on and connecting the stringers, each of the stringers comprising an elongated supporting block coextensive in length with the floor rack to rest on the floor of the car, an inverted channel shaped supporting strip coextensive with and fitting slidably over the block, means connecting the strip and block for limited vertical movement, and an elongated sinuous spring strip within the channel shaped supporting strip resting on the block to urge the supporting strip upward relative to the block.

4. A floor rack for railway cars and the like comprising a plurality of stringers and slats supported on and connecting the stringers, each of the stringers comprising an elongated supporting block coextensive in length with the floor rack to rest on the floor of the car, an inverted channel shaped supporting strip coextensive with and fitting slidably over the block, means connecting the strip and block for limited vertical movement, and a resilient block of rubber-like material within the channel shaped supporting strip and resting on the block to urge the supporting strip upward relative to the block.
